INVENTOR:
Frederick Goerig.
BY
Graentzel and Richard,
ATTORNEYS.

UNITED STATES PATENT OFFICE.

FREDERICK GOERTZ, OF NEWARK, NEW JERSEY, ASSIGNOR TO AUGUST GOERTZ & CO.,
A CORPORATION OF NEW JERSEY.

VANITY BOX.

Application filed July 8, 1924. Serial No. 724,780.

This invention relates, generally, to improvements in that class of cases or boxes known in the art as vanity boxes, adapted to contain face-powders, rouges, cosmetics, and the like; and, the present invention has reference, more particularly, to a novel and simply constructed vanity box or case, comprising two compartments or chambers, one adapted to contain a face-powder, or the like, and the other compartment or chamber being adapted to contain a compact of pink or red rouge, the case or box being formed principally by a dividing partition or tray, and a band surrounding the marginal edge of the said partition or tray, all being secured by a hinge-member and fastening-lugs, thereby providing a combined interlocked and frictionally bound assemblage of the several elements.

The invention has for its primary object to simplify the general construction of the main body of the case or box, by doing away with the more or less expensive structure of a main compartment-shell, usually drawn into shape by means of expensive machinery or dies; and, furthermore, to provide a vanity or other box or case in which all the various members thereof are secured and positively maintained in the assembled relation, without any use of solder, or independent rivets.

The invention has for its further object to provide a vanity case or box in which the main portions of the box which provide the usual compact-receiving compartments of the device are arranged in a manner, and are of such a construction that the thickness of the box has been reduced to a minimum, and whereby an extremely thin vanity-box is the result.

The present invention has for its further object to provide a vanity case or box in which the covers or lids of the case are of such construction, so that the annular flange-members of the respective covers will close within or inside of the band encircling the hereinbefore-mentioned partition; and, furthermore, the said band being in a flat condition, before assemblage in the form of a cylindrical box or case, can be readily ornamented, by engraving, or by its passage between suitable ornamented rolls.

Other objects of the present invention not at this time more particularly enumerated

will be clearly understood from the following detailed description of the said invention.

With the various objects of the invention in view, the said invention consists, primarily, in the novel vanity case or box hereinafter set forth; and, the said invention consists, furthermore, in the novel arrangements and combinations of the various devices and parts, as well as in the details of the construction of the said parts, all of which will be more fully described in the following specification, and then finally embodied in the clauses of the claims, which are appended to and which form an essential part of the said specification.

The invention is clearly illustrated in accompanying drawings, in which:

Figure 1 is a perspective view of a vanity case or box, illustrating one embodiment of the principles of the present invention, the various members of the case or box being shown in their closed relation; Figure 2 is a view of the case or box, with all of the members of the same being represented in their opened relation, and Figure 3 is another view of the case or box, with only one of its members, in this case the compact-holder, being represented in its opened relation.

Figure 4 is a view of the vanity case or box, partly in elevation and partly in vertical section, when looking toward the hinge-connection of the case or box.

Figure 5 is a transverse vertical sectional representation of the main portion of the vanity case or box, looking toward the hinge-connection of the same, with the covers or lids shown in their opened relation to the said main portion, and showing in connection with said covers or lids, the cover-inserts used therewith.

Figure 6 is a vertical section, taken on line 6—6 in said Figure 5; Figure 7 is a similar section, taken on line 7—7 in said Figure 6; Figure 8 is a horizontal sectional representation of the main body-portion of the case or box, taken centrally through the above-mentioned band and the hinge-connection of the device; and Figure 9 is a perspective view, collectively, of the said band and one of the members of the hinge-connection.

Figure 10 is a view, similar to said Figure

8, illustrating a slightly modified construction of a vanity-case or box; and Figure 11 is a perspective view of the modified form of band employed in the construction of said case or box.

5 Similar characters of reference are employed in all of the said above described views, to indicate corresponding parts.

Referring now to the several figures of the drawings, the reference-character 1 indicates the herein-above mentioned partition, the same being preferably of a circular marginal configuration, bounded by a right-angled flange 2. It will be understood, however, 10 that the marginal configuration of this partition, and of the said flange 2 may be varied, and may be of any other suitable shape. At a suitable location the flange 2 is provided with a pair of perforations or slits, as 3, and 15 surrounding the said flange 2 is a band or strap 4, preferably of the shape illustrated more particularly in Figure 9 of the drawings, the said band or strap being of such length, so that when it is arranged about the 20 said flange 2, a hinge-plate receiving space 5 will be provided. The end-portions of the said band or strap 4, which are preferably reduced, as at 6, are provided with suitable 25 perforations or slits 7 corresponding to and being adapted to be brought into registration with the said perforations or slits 3, as indicated in Figure 8 of the drawings.

The means for securely affixing the said band or strap 4 about the said flange 2 is by 30 means of a suitably shaped hinge-plate 8, see Figure 9, said plate being placed in or directly above the space 5; and, being provided at its ends with fastening lugs or tongues 9, these lugs or tongues are suitably 35 bent, and then inserted through the registering perforations or slits 7 and 3, and then firmly forced over upon the inner surface-portion of the flange 2, substantially as shown in the several figures of the drawings. 40 In this manner, the said band or strap will be permanently and immovably secured to the said partition 1, and the said band or strap being of greater width than that of the flange 2, a main body-element is produced, 45 having two compartments 10 and 11 arranged on opposite sides of the partition 1, as will be clearly evident from an inspection of Figures 4 and 5 of the drawings. Along its marginal edges 12 and 13, the said hinge-plate 8 is provided with pairs of suitably 50 disposed pintle-receiving ears or lugs 14 and 15. Pivotaly connected with one pair of said ears or lugs, as 14, by means of a correspondingly placed pintle-lug or ear 17 is 55 a suitably formed lid or cover 16, which is marginally bent, so as to provide a stop-bead, as 18, and has a marginal closing flange 19, adapted, when the lid or cover 16 is closed, to enter within the compartment 10, as indicated in Figure 4 of the drawings. As

shown more particularly in Figure 5 of the drawings, the said closing flange 19 is cut away, the end-portions 20 and 21 being inwardly bent or curved, the pintle-receiving lug or ear 17 being arranged between these 70 inwardly bent or curved end-portions 20 and 21. In closing the lid or cover, these inwardly bent or curved end-portions will readily enter the correspondingly cut-away portion of the band or strap 4, so as to bring the flange 19 into frictional binding engagement with the adjacent inner surface-portions of the said band or strap 4. Likewise, there is pivotally connected with the other pair of ears or lugs 15, by means of a 75 correspondingly placed pintle-lug or ear 23, a suitably formed lid or cover 22, which is also marginally bent, so as to provide a stop-bead, as 24, and has a marginal flange 25 which is adapted when the lid or cover 22 is 80 closed, to enter within the compartment 11.

From said Figure 5, it will also be seen, that the closing flange 25 is also cut away, the end-portions 26 and 27 being inwardly bent or curved, the pintle-receiving lug or 85 ear 23 being arranged between these inwardly bent or curved end-portions 26 and 27. In closing the lid or cover these inwardly bent or curved end-portions will readily enter the correspondingly cut-away portion 90 of the band or strap 4, so as to bring the flange 25 into frictional binding engagement 95 with the adjacent inner surface-portions of the said band or strap 4.

Within the said lid or cover 16 is disposed 100 a correspondingly shaped mirror 28, suitably held in place by means of a retaining ring 29 which is forced into frictional holding engagement with the closing flange 19 of the said lid or cover 16, but which mirror 105 may be otherwise secured in said lid or cover in any other suitable manner.

Referring now to Figure 6 of the drawings, it will be seen that within the other lid or cover 22 is disposed a suitably formed plate 30, preferably provided with a marginal flange 31, for forcing said plate into frictional holding engagement with the inner surface-portions of the marginal flange 25 of the said lid or cover 22, as will be evident. 110 The said plate 30, however, may be otherwise secured within the said lid or cover. As shown, this plate 30 is made with a suitably shaped compact-receiving opening, as 32, which is partially bounded by a retaining flange 33, or other means for receiving and 115 maintaining the usual rouge-compact in its operative position within the said lid or cover 22.

In lieu of the form of band or strap 4 illustrated in connection with Figures 1 to 9 of the drawings, this strap may be made in the form of a band 34, such as is indicated more particularly in Figures 10 and 11, the said band 34 being forced directly 120

over the partition-member, and in this instance being marginally cut away, as at 35 and 36, and being provided with the suitably disposed perforations or slits 37 for the reception of the fastening lugs or tongues 9 of the hinge-plate 8, substantially as illustrated in said Figure 10. The construction and arrangement of the other parts of this modified form of vanity case or box 10 is the same as that hereinabove described in connection with the construction of case or box illustrated in said Figures 1 to 9, and any further description of the same is therefore deemed unnecessary.

15 From the foregoing description of the present invention, it will be clearly seen, that I have provided a neat and compact assemblage of the various elements comprising the vanity case or box, the said various 20 elements being easily and quickly assembled and maintained in their assembled relation without the employment of solder, rivets, or the like.

Of course I am fully aware, that changes 25 may be made in the general arrangements and combinations of the various devices and parts, as well as in the details of the construction of the said parts, without departing from the scope of the present invention 30 as set forth in the foregoing specification, and as defined in the clauses of the claims which are appended thereto. Hence, I do not limit my present invention to the exact arrangements and combinations of the 35 various devices and parts, as described in the said specification, nor do I confine myself to the exact details of the construction of the said parts, as illustrated in the accompanying drawings.

40 I claim:—

1. A vanity case comprising a partition-member, a band marginally encircling said member, a hinge-member secured to said band, and a pair of cover-members pivotally connected with said hinge-member, said cover-members being provided with right-angled closing flanges adapted to enter into closing engagement with the inner surface-portions of said band.

45 2. A vanity box comprising a partition-member, a band marginally encircling said member, and a hinge-member carrying cover-members, all being secured by said hinge-member, so as to provide a combined

interlocked and frictionally bound assemblage of said members, said cover-members being provided with right-angled closing flanges adapted to enter into closing engagement with the inner surface-portions of said band. 55

3. A vanity case comprising a partition-member, a band marginally encircling said member, said band being provided with lug-receiving slits, a hinge-member, fastening-lugs extending from said hinge-member, said lugs entering said slits for securing said hinge-member to said band, and a pair of cover-members pivotally connected with said hinge-member, said cover-members being provided with right-angled closing flanges 60 65 adapted to enter into closing engagement with the inner surface-portions of said band. 70

4. A vanity case comprising a partition-member bounded by a right-angled flange, said flange being provided with lug-receiving slits, a band encircling said partition-member, said band being also provided with lug-receiving slits registering with the slits in the flange of said partition-member, a hinge-member, fastening lugs extending 75 80 from said hinge-member, said lugs entering the registering slits for securing said partition-member, said band and said hinge-member in assembled relation, and a pair of cover-members pivotally connected with said hinge-member. 85

5. A vanity case comprising a partition-member bounded by a right-angled flange, said flange being provided with lug-receiving slits, a band encircling said partition-member, said band being also provided with lug-receiving slits registering with the slits in the flange of said partition-member, a hinge-member, fastening lugs extending 90 95 from said hinge-member, said lugs entering the registering slits for securing said partition-member, said band and said hinge-member in assembled relation, and a pair of cover-members pivotally connected with said hinge-member, said cover-members being 100 provided with right-angled closing flanges adapted to enter into closing engagement with the inner surface-portions of said band.

In testimony, that I claim the invention set forth above I have hereunto set my hand 105 this 1st day of July 1924.

FREDERICK GOERTZ.
